UNITED STATES PATENT OFFICE.

FRANK P. MILLER, OF MEADVILLE, PENNSYLVANIA.

REAMER.

1,244,227.

Specification of Letters Patent. Patented Oct. 23, 1917.

Application filed November 22, 1916. Serial No. 132,760.

To all whom it may concern:

Be it known that I, FRANK P. MILLER, a citizen of the United States, and a resident of Meadville, in the county of Crawford and State of Pennsylvania, have invented a new and Improved Reamer, of which the following is a full, clear, and exact description.

Among the principal objects which the present invention has in view are: to tighten inserted knives in a cutter head; to reinforce the seating pressure thereon; to permit unrestricted movements of the cutting members; to hold said members in adjusted position; and to lock said cutting members positively in said cutter head against displacement.

Drawings.

Figure 1 is a side view of a cutting head provided with cutters and means for holding the same, all constructed and arranged in accordance with the present invention; Fig. 2 is a longitudinal section, the section being taken as on the line 2—2 in Fig. 3;

Fig. 3 is an end view of the cutter head partly in section, the view being taken as on the line 3—3 in Fig. 1;

Fig. 4 is a view of a modified form of cutter and key member therefor;

Fig. 5 is a similar view of a further modified form of the invention.

Description.

The invention as shown in the drawings is applied to a reamer head 10. The head 10 is furnished with a series of blade-holding slots, the bottoms 11 of which slots are inclined. The slots 12 which form the bottoms 11 extend through a reducing screw-threaded section 13, the threads whereof are engaged by threads on a thrust collar 14, the inclined surface 15 whereof corresponds with and overhangs the inclined abutting edges of the cutters 16. The collar 14 is held in adjusted position by a lock ring 17.

The cutters 16 are held by fillets 18 in outwardly-opening grooves provided in the head 10, the sides of which grooves are parallel. The rear wall in each groove against which the back of a cutter rests, is preferably perpendicular to the bottom 11 of said groove. The fillets 18 are disposed

in grooves 19 in the opposite side or face of each cutter. The grooves 19 are complementary to grooves 20 which are formed in the heads 10 and in the advance side of each of the slots 12. The grooves 19 and 20 are parallel with the bottoms 11 of the slots for permitting endwise movement of said cutters in said slots 12. Preferably the fillets 18 are circular in cross section.

A portion of the wall of each of said grooves 19 and 20 are cylindrical and a portion straight or tangential. In the original disposition of the said grooves, the cylindrical walls are concentric. As the groove of the cutter in which the groove 19 is formed wears, the cylindrical walls are forced apart, the cylindrical wall of the groove 19 being moved slightly toward the bottom 11 of the slot 12.

The purpose in employing the fillets 18 is to lock the cutters 16 rigidly in the reamer head 10, and the adjusting screws 21 are employed to reinforce this locking effect and to force the blade 16 over and downward against the sides and bottoms respectively of the slots 12, this also counteracting any wear on the cutters 16 or slots 12 which otherwise would loosen the cutter in the heads 10 and slots 12. Each of the screws 21 has a head 22, the under side of which is tapered to bear against the side of a fillet 18 to wedge the same toward the cutters 16. This construction is best shown in Fig. 3 of the drawings.

To receive each of the screws 21, a tapped hole 23 is formed, which has at the outer end thereof a socket 24 into which the head 22 may be inserted. The object of this is to exert an even pressure on the fillets 18 and the cutters 16 connected therewith.

In the modified form of the invention shown in Fig. 4, the groove 25 is stopped short of the cutting edge of the blade 16 to permit the use of the same for service pressing.

In the modified form of the invention shown in Fig. 5, a ridge 26 is formed integral with the cutter 16 as a substitute for the fillets 18 of the earlier described form of the invention.

In practice it will be observed that when any cutter 16 is to be removed, the screws 21 are preliminarily loosened until the pressure of the heads 22 thereof is removed from the fillets 18 with which said screws coöperate.

The particular cutter 16 and fillet associated therewith is then drawn from the head and from the slot 12 in which it is disposed.

When the cutters 16 are placed in the head

- 5 10 and slots 12 thereof, the screws 21 are set up until the tapered portion thereof under the heads 22 of the said screws engages the fillets 18 and wedges the same hard against the cutters 16, forcing the said cutters firmly against the side wall and bottom of the slots 12 to prevent chatter or dislodgment of said cutters. Owing to the formation of the grooves 19 and 20, the fillets 18 on the grooves 19 are pressed downward.
- 10 15 The removal of the metal of the head 10 to form the straight wall of the groove 20 permits this movement of the fillets 18. In this manner the cutters 16 are forced and held more readily in the slots 12 than would 20 otherwise result.

While the slots 12 in the reamer head 10 have been shown and described as having bottoms 11 inclined rearwardly, a similar result may be obtained by reversing the inclination of the bottoms 11 so that instead of expanding the cutters 16 as they are drawn from said slots, they will expand when they are moved into said slots.

Claims.

- 30 1. A reamer comprising a head having a plurality of outwardly opening slots for holding cutters, said slots having inclined bottoms, a plurality of cutters having inclined base surfaces, wedging members op-

eratively held in said head adjacent said slots and a plurality of longitudinally extending fillets disposed between said cutters and said wedging members and inside of the periphery of the head and engaged by said members to force the cutters against one wall and the bottoms of the slots.

2. A reamer comprising a head having a plurality of outwardly opening slots for holding cutters, said slots having inclined bottoms and longitudinal grooves, a plurality of cutters having inclined base surfaces and longitudinal grooves, a plurality of screws operatively mounted in said head adjacent said slots, said screws having laterally extended heads and tapered sections intermediate the peripheries of said heads and the peripheries of the shanks of said screws; and a plurality of cylindrical key rods in the grooves of the head and cutters for engagement by the tapered sections of the screws.

3. A reamer comprising a head having formed therein a series of parallel slots, each of said slots having in one wall thereof a key groove; a plurality of cutters, each of said cutters having a key groove formed in the face thereof, said groove being complementary to the first-mentioned groove; a plurality of removable fillet members adapted to rest in said grooves; and means engaging said fillet members for pressing said cutters against one wall and the bottoms of said slots.

FRANK P. MILLER.
